WILLIAM COGGESHALL, OF SPRINGFIELD, OHIO, AND JOHN W. STANLEY, OF CHICAGO, ILLINOIS.

Letters Patent No. 92,585, dated July 13, 1869.

IMPROVEMENT IN PULVERIZING AND MIXING-CYLINDERS.

The Schedule referred to in these Letters Patent and making part of the same.

To whom it may concern:

Be it known that we, WILLIAM COGGESHALL, of Springfield, in the county of Clark, and State of Ohio, and JOHN W. STANLEY, of Chicago, in the county of Cook, and State of Illinois, have invented a new and useful Improvement in Pulverizing and Mixing-Cylinders; and we do declare that the following is a true and accurate description thereof, reference being had to the accompanying drawings, and to the letters of reference marked thereon, and being a part of this specification, in which—

Figure 1 is a perspective view of our invention, with a portion of the cylinder broken out, to show its interior arrangement, and

Figure 2 is a cross-section of the same.

Figure 3 is a vertical section of the interior arrangement.

Like figures indicate like parts in each figure.

The nature of this invention relates to the construction of an apparatus for pulverizing paints, drugs, and other materials, placed within a revolving cylinder, by the action thereon of one or more heavy metallic rollers, revolving by their own gravity, at the bottom of the cylinder, and in an arrangement for thoroughly mixing the pulverized contents of the same.

A, in the drawings, represents a proper frame, surmounted by bearings B, in which revolves a shaft, C, carrying a strong metallic cylinder, D, having in its periphery a longitudinal opening, closed, when in operation, by a door, E.

The cylinder may receive its motion through proper gearing from an intermediate shaft, as shown, or in any other suitable manner.

F are rollers, of any hard metal, loosely placed in the bottom of the cylinder, extending its length, and guided between the annular flanges G, fig. 2, projecting inward from the heads d of the cylinder, their weight causing them to gravitate to the lowest point in the cylinder, rolling over and pulverizing the material contained in it.

H are rods or bars, extending the length of the cylinder, and secured to the heads within the annular flanges G.

These rods are provided with flights h, projecting outwardly from the same, and which resemble, in form, segments of a screw-thread of long pitch, for thoroughly mixing the pulverized contents of the cylinder, the pitch of those of one rod being in opposition to those on the other.

Its operation may be explained as follows:

Supposing that it is desired to pulverize an adulterated article of paint, the requisite quantity of ground lead, barytes, and coloring-matter, in their proper proportions, being placed in the cylinder, its door E is securely closed, and it is caused to revolve. The heavy rollers F, seeking the lowest part of the cylinder, will roll over and in the mixture, and speedily reduce it to powder; the annular flanges G preventing the rollers from rising above the mixture, while the flights h, passing through it, mix it intimately.

When the mixture is pulverized to the proper degree, the revolution of the cylinder is stopped, and the door removed, when a few turns will discharge its contents in a drawer in the lower part of the frame A, it being understood that a proper casing surrounds the cylinder while being discharged.

What we claim as our invention, and desire to secure by Letters Patent, is—

The cylinder D, provided with annular flanges G, stationary rods or bars H, flights h, and rollers F, all arranged to operate substantially as described, and for the purposes specified.

WILLIAM COGGESHALL.
JOHN W. STANLEY.
